UNITED STATES PATENT OFFICE.

ARNOLD S. BERTELS, OF TENAFLY, NEW JERSEY, ASSIGNOR TO WESTERN ELECTRIC COMPANY, INCORPORATED, OF NEW YORK, N. Y., A CORPORATION OF NEW YORK.

TESTING SYSTEM FOR AUTOMATIC TELEPHONE SWITCHES.

Application filed July 23, 1923. Serial No. 653,125.

To all whom it may concern:

Be it known that I, ARNOLD S. BERTELS, a citizen of the United States of America, residing at Tenafly, in the county of Bergen, State of New Jersey, have invented certain new and useful Improvements in Testing Systems for Automatic Telephone Switches, of which the following is a full, clear, concise, and exact description.

10 This invention relates to a telephone exchange system and more particularly to a testing system for use in a machine switching system for testing selector switch units.

It is an object of this invention to provide

15 an improved testing system.

The switching units of an automatically operated telephone exchange are made up of control apparatus, relays and auxiliary circuits to control its automatic progression

20 and further control other switching units and the line. A large number of such switching units are required in a system of this kind, any one of which may be arbitrarily selected, when idle, to complete a 25 service connection. Thus, it is apparent that a switching unit giving inefficient service is not immediately noticed. Since the apparatus of a switching unit requires adjustments within limited variation, it is im-

30 portant that these units be regularly tested to determine their ability to render efficient service. In order to reduce the cost of such maintenance, it is desirable to use a testing system requiring a limited amount of manual operation.

35 A feature of this invention is in the use of a common testing device.

40 A further feature of this invention is in the use of a common testing device to be seized by the automatic switch under test.

45 A further feature of this invention is in the provision of a common auxiliary testing device or devices used in conjunction with a main testing device.

50 A further feature of this invention relates to the use of an auxiliary testing device seized under the control of a main testing device.

55 The selector switch disclosed in this application is designed to associate itself with a line and to automatically connect continuous ringing potential to the line conductor as soon as the line is found to be idle. In this operation, which is termed "immediate ringing" the ringing potential is connected

to the line for a predetermined period of time. Following the application of immediate ringing an interrupter is automatically connected to the line through which ringing potential is intermittently connected to intermittently ring the bell at the subscriber's station. The ringing potential, either continuous or interrupted, is disconnected at the selector switch upon the removal of the receiver from the switchhook at the subscriber's station. A relay termed the "ringing relay" in the selector switch operates to remove the ringing potential upon the elevation of the switchhook.

60 It is therefore an additional object to test selector switch units provided with ringing equipment.

65 The following features are incident to the attainment of this additional object.

70 A feature of this invention is in the provision of a primary testing device, equipped with keys, to function as the register of a sender, in combination with a progression switch, to automatically control the connection of an incoming selector switch to one 75 of a plurality of secondary testing devices. The primary testing device remains positioned in such manner as to receive a signal upon the satisfactory completion of tests 80 by the secondary testing device.

85 A further feature of the invention is the provision of means for testing the adjustments of the ringing apparatus of a selector switch with an automatically progressive testing device controlled by the automatically operating ringing apparatus of said selector switch.

90 A further feature of the invention relates to the automatic starting of the testing device from application of ringing potential 95 and ringing ground by the selector switch.

95 A further feature of the invention relates to the response of the testing device to the application of immediate ringing potential 100 by the selector switch and means for determining that immediate ringing and not interrupted ringing potential is first connected to the line conductors.

105 A further feature of the invention relates to the provision of means for properly recognizing the interrupted ringing potential during the tests of that feature.

110 A further feature of the invention resides in the provision of means for synchronizing the progressive movement of the auto-

matic testing device with the automatic application of ringing potential.

A further feature of the invention resides in the provision of means for making a plurality of false operation tests to determine whether the ringing relay in the selector switch will operate falsely preceding the removal of the receiver from the switch-hook. A plurality of tests are made so that 10 one or more of these tests may be obtained at a time when the ringing current wave is of maximum strength.

A further feature of the invention resides in automatic means for applying an operating test to the ringing relay in such manner that sluggish operation of said relay is detected.

A further feature of the invention relates to the provision of means for determining 20 the success of the operating test of the ringing relay.

A further feature of the invention relates to means, at the termination of the selector switch ringing apparatus tests, to test the 25 adjustment of the selector switch supervisory relay and means included in this test to operate a signal to indicate to a test-man that the apparatus in the selector switch under test is in correct adjustment.

30 These and other features of the invention will be apparent from the following description taken in connection with the accompanying drawings.

While the invention has been disclosed as 35 particularly adapted for testing switches of the panel type it will be apparent, however, from the following description that the invention has a wider utility and that by slight modification it could be adapted for 40 testing other types of selector switches.

Figs. 1 and 2 show a testing and controlling circuit for directing the incoming selector switch and the final selector switch to an automatic testing device that is 45 permanently connected to the multiple terminals of the multiple frame.

Fig. 3 shows the incoming selector switch to be tested.

Fig. 4 shows a final selector switch used 50 to connect the incoming selector switch to the testing device, Fig. 5.

Fig. 5 shows the automatic testing device to which the incoming selector is connected for test. This testing device is connected to 55 terminals in the final frame in place of lines extending to subscriber's stations.

Description of apparatus.—The key set shown in Fig. 1 is made up of mechanically locking keys. The switch shown in Fig. 2 60 is of a well known step-by-step type.

The automatic selector switch shown in Figs. 3 and 4 are of the well known power driven type in which a plurality of sets of brushes are mounted on a vertical brush shaft arranged to be selectively tripped 65

into engagement with an individual sequence of banks. The brush shafts are propelled in a vertical direction by means of constantly rotating power drums. In general construction and operation these 70 switches are both of the same character as the one shown and described in detail in Patent No. 1,123,696 issued January 5, 1915, to Edward B. Craft and John N. Reynolds. More specifically, the incoming selector shown in Fig. 3 and the final selector shown in Fig. 4 are described in Patent No. 1,395,977 issued November 1, 1921, to Franklin A. Stearns and Frederick J. Scudder. 75

The sequence switch shown in Fig. 5 is of 80 the same general type as used in Figs. 3 and 4.

General description.—The test-man before proceeding with a test of an incoming selector inserts plug 234 into jack 304 and plug 232 into jack 231. Certain of keys 130 to 169 are then actuated to register the line number to which the incoming selector switch is directed. A start key 240 is then actuated by the test-man and from this 85 point the operation is automatic until such time as trouble is encountered in the incoming selector switch or a signal is received by the test-man that an incoming selector switch has been tested and its apparatus 90 found to be in correct adjustment. 95

Upon the actuation of the start key a progressively operated switch is actuated and in its progressive movement establishes 100 circuits for directing the incoming selector switch to a particular final selector switch and the final selector switch is directed to an automatic testing device connected to certain final multiple terminals.

The incoming selector switch performs its 105 functions the same as when it is connected to a line extending to a subscriber's station. The ringing potential is thus connected to the testing circuit and is used as an automatic starting means to actuate the apparatus of the testing device, Fig. 5.

Various tests are now made of the ringing apparatus in the incoming selector switch, Fig. 3, to determine the accuracy of 110 its adjustments. These tests are made throughout the progressive operation of the testing device until the ringing relay 314 is caused to operate thus rotating the incoming selector sequence switch into talking position. Following the operating test of the ringing relay 314, the testing device progresses to a position of its switch for testing the supervisory relay of the incoming selector switch. The test applied to the supervisory relay 312 causes it to intermittently operate and release, thus connecting ground through its armatures and contact to the winding of a relay in the testing control circuit, Fig. 2. The intermittent operation of the relay in Fig. 2 establishes a cir- 115 120 125 130

cuit for flashing a lamp to indicate to the test-man that the test of the incoming selector switch is completed and its apparatus is in proper adjustment.

Having now described in a general way the apparatus employed in conducting tests and the manner in which it is to be used, it is thought that the invention will be better understood by a consideration of the specific manner in which it functions.

Detailed description.—It will be remembered from the general description that the test-man will first insert plug 232 into jack 231 and plug 234 into jack 304 of the particular incoming selector to be tested. He will then consult his chart and depress the proper keys shown in Fig. 1 to control the incoming and final selector switches to select the line connected to the testing device shown in Fig. 5. Assuming that the testing device is connected to line 3190, keys 133, 141, 159 and 160 will be actuated. The actuation of the above-designated keys will associate certain of the counting relays with the terminals of terminal arc 250, the functioning of which will be described hereinafter.

Key 240 is now actuated by the test-man to start the automatic progression of switch 200. The actuation of key 240 establishes a circuit for operating relay 213 which may be traced from grounded battery through the winding of relay 213, contacts of key 240, right outer normal contact and armature of relay 212, terminal 1 of terminal arc 250 to ground through brush 204. If the incoming selector switch, Fig. 3, is made busy from seizure by another selector switch, a circuit will be established for operating relay 210. This circuit may be traced from ground connected to the sleeve of jack 304, sleeve of plug 234, sleeve conductor of patching cord 233, sleeve of plug 232, sleeve of jack 231, brush 205, terminal 1 of terminal arc 254, right normal armature and contact of relay 217, winding of relay 212 to battery. Relay 212 in attracting its right armature establishes a circuit for lighting lamp 228 to indicate the busy condition to the test-man. The circuit for lighting lamp 228 may be traced from ground through brush 204, terminal 1 of terminal arc 253, right armature and contact of relay 212, lamp 228, resistance 223 to grounded battery. The circuit for actuating relay 213 upon the operation of key 240 is also opened at the right armature of relay 212. The operation of relay 212 prevents the procedure of test of a selector switch that is busy. Assuming that the incoming selector switch, Fig. 3, is idle, relay 213 is operated through the circuit established and traced upon the operation of key 240.

The relay 213, in attracting its left and right armature, establishes a locking circuit

for itself and an operating circuit for relay 217 which is effective upon the release of key 240. This circuit may be traced from grounded battery through the winding and left armature and contact of relay 213, winding of relay 217, right contact and armature of relay 213, left normal armature and contact of relay 211 to ground through contact and armature of relay 11. Relay 217 in attracting its left armature establishes a circuit for actuating switch magnet 200 which may be traced from grounded battery through the winding and contact of switch magnet 200, brush 203, terminal 1 of terminal arc 252, armature and contact of relay 217 to ground through right contact and armature of relay 220. The switch is thus rotated from terminal 1 to terminal 2.

Brush 204 in contact with terminal 2 to terminal 21 of terminal arc 243 establishes a circuit for actuating relay 221. This may be traced from grounded battery through winding of relay 221, terminals 2 to 21 of terminal arc 253, brush 204 to ground. The circuits established by relay 221 in attracting its armatures connect the incoming selector to the testing control circuit. These leads are normally held open to prevent connection of the testing control circuit to a busy incoming selector switch.

Brush 203 in contact with terminal 2 of terminal arc 252 establishes a circuit for energizing switch magnet 200 which may be traced from grounded battery through the winding and contacts of switch magnet 200, brush 203, terminal 2 of terminal arc 252 to ground, thus rotating the switch to terminal 3.

Brush 202 in contact with terminal 3 of terminal arc 251 establishes a circuit for operating relay 10. This may be traced from grounded battery through the winding of relay 10, terminal arc 251, brush 202 to ground. The actuation of relay 10 connects grounded battery through its five right armatures and contact to the windings of counting relays 0 to 9 and in attracting its left armature establishes a circuit for operating relay 220. This may be traced from grounded battery through the armature and contact of relay 10, winding of relay 220 to ground. Relay 220 in attracting its armature establishes a circuit for actuating switch magnet 200. This may be traced from grounded battery through the winding and contacts of switch magnet 200, brush 203, terminal 3 of terminal arc 252 to ground through contact and armature of relay 220, thus rotating the switch from terminal 3 to terminal 4.

With the switch brushes connected to terminal 4 the fundamental circuit for incoming brush selection is established.

The fundamental circuit may be traced

from grounded battery through the right winding of relay 311, Fig. 3 upper contacts of sequence switch spring 321, resistance 315, upper contact of sequence switch spring 324, tip of jack 304, tip of plug 234, tip conductor of patching cord 233, tip of plug 232, tip of jack 23, outer right contact and armature of relay 221, brush 206, terminal 4 of terminal arc 255, left winding of relay 214, 5 winding of relay 215, contact and armature of counting relay 0', inner left normal contact and armature of relay 212, inner left armature and contact of relay 221, ring of jack 231, ring of plug 232, ring conductor 10 of patching cord 233, ring of plug 234, ring of jack 304, lower contact of sequence switch spring 323, resistance 316 to ground through lower contact of sequence switch spring 325. Relays 311 and 215 are operated in this 15 circuit. Relay 214, however, does not operate at this time since it is polarized in the opposing direction to the current flow.

Relay 311 in attracting the left outer armature establishes a circuit for energizing sequence switch magnet 300. This circuit may be traced from grounded battery through winding of magnet 300, lower contact of sequence switch spring 328, left outer spring and armature of relay 311, to ground to lower contact of sequence switch spring 322. The sequence switch is thus rotated from position 1 to position 2 where a holding circuit is established for relay 311. This may be traced from grounded battery through the right winding of relay 311, right upper and lower contacts of sequence switch spring 321, right contact and armature of relay 311, left upper and lower contacts of sequence switch spring 336, resistance 315, upper contacts of sequence switch spring 324, tip spring of jack 304, tip of plug 234, tip conductor of patching cord 233, tip of plug 232, tip spring of jack 231, left outer contact and armature of relay 221, brush 206, 40 terminal 4 of terminal arc 255, left winding of relay 204, winding of stepping relay 215, armature and contact of counting relay 0', left inner normal contact and armature of relay 212, left inner armature and contact of relay 221, ring spring of jack 231, ring of plug 232, ring conductor patching cord 233, ring of plug 234, ring spring of jack 304, lower contact of sequence switch spring 323, resistance 316 to ground through lower 55 contact of sequence switch spring 335.

In sequence switch position 2, a circuit is also established for energizing up-drive magnet 302. This may be traced from grounded battery through the winding of up-drive magnet 302, left upper contact of sequence switch spring 334, left outer contact and armature of relay 311 to ground through lower contact of sequence switch spring 322. The selector switch elevator is 60 now driven upward in the manner well

known in the art, and in its upward movement brush 341 is intermittently brought into contact with the conducting portion of commutator segment 344. Thus a shunt circuit is established to cause the intermittent 70 deenergization of stepping relay 215. This shunt circuit may be traced from ground through the lower contact of sequence switch spring 333, brush 341, commutator 75 344, right lower contact of sequence switch spring 336 to a junction point in the circuit established for operating relays 311 and 215. The shunt will not cause the release of relay 311 but will cause the release of relay 215. 80

The initial operation of relay 215 over the fundamental circuit establishes a circuit for operating counting relay, 1. This may be traced from ground through the armature and contact of relay 215, brush 201, 85 terminal 4 of terminal arc 250, left contacts of key 133, winding of counting relay 1, fifth right contact and armature of relay 10 to grounded battery. The operation of counting relay 1 establishes a locking circuit for itself and an operating circuit for counting relay 0' which is effective upon the first release of stepping relay 215. This circuit may be traced from ground through the armature and contact of counting relay 0' 90 windings of counting relays 0 and 0' to grounded battery through fifth right contact and armature of relay 10.

The upward movement of the incoming selector switch elevator causes brushes 341 100 to move from the conducting portion of commutator segment 344 to an insulated portion of this segment which will remove the shunt from stepping relay 215 and cause its reoperation over the original circuit traced to battery through relay 311. This operation of relay 215 will establish a circuit for operating the counting relay 0 which may be traced from ground through the armature and contact of relay 215, brush 201, 105 terminal 4 of terminal arc 250, left contacts of key 133, armature and contact of counting relay 1', winding of counting relay 0, fifth right contact and armature of relay 10 to grounded battery. The upward movement of the incoming selector switch elevator will again establish the shunt circuit causing the release of stepping relay 215. Upon the release of relay 215 the circuit established by the operation of counting relay 0 is effective for operating counting relay 0' and relay 11. This may be traced from ground through armature and contact of counting relay 0', 110 over a divided path through the windings of counting relay 0' and a relay 11 in multiple, thence through the winding of counting relay 0, fifth right contact and armature of relay 10 to grounded battery. 115

The operation of counting relay 0' opens 120

the fundamental circuit to cause the release of relay 311 which is effective as soon as brush 341 is moved to the insulated portion of commutator segment 344 next above the 5 conducting segment that caused the second release of stepping relay 215. The release of relay 311 arrests the upward movement of the incoming selector switch elevator and establishes an actuating circuit for sequence 10 switch magnet 300 which may be traced from grounded battery through the winding of sequence switch magnet 300, left upper contact of sequence switch spring 328 to ground through the left inner armature 15 and contact of relay 311, rotating the sequence switch from position 2 to position 3.

Relay 11 in attracting its armature opens the holding circuit for relays 213 and 217 which release, and also establishes a circuit for actuating switch magnet 200. This actuating circuit may be traced from grounded battery through the winding and contacts of switch magnet 200, brush 203, terminal 4 of terminal arc 252 to ground 20 through contact and armature of relay 11. Thus the switch is rotated from terminal 4 to terminal 5. The actuating circuit for relay 10 is now open, causing its release. The release of relay 10 causes the release 30 of counting relays and relay 220 held in an operated position through its contacts. The release of relay 220 establishes an energizing circuit for switch magnet 200 which may be traced from grounded battery through the winding and contacts of switch magnet 200, brush 203, terminal 5 of terminal arc 252 to ground through contact and armature of relay 220. The switch is thus rotated from terminal 5 to terminal 6.

40 Brush 202 in contact with terminal 6 of terminal arc 251 establishes an actuating circuit for relay 10. This may be traced from grounded battery through the winding of relay 10, terminal 6 of terminal arc 251, brush 202 to ground. Relay 10 in attracting its right armatures establishes a source of grounded battery for operating the counting relays and in attracting its left armature establishes an actuating circuit for relay 220. The actuating circuit for relay 220 may be traced from grounded battery through the left armature and contact of relay 10, winding of relay 220 to ground. The operation of relay 220 establishes a circuit for actuating switch magnet 200 which may be traced from grounded battery through the winding and contacts of switch magnet 200, brush 203, terminal 6 of terminal arc 252, contact and armature of relay 220 to ground. The switch is thus rotated to terminal 7 where the fundamental circuit is again established for incoming group selection.

65 The fundamental circuit is the same as previously traced with the exception that

position 3 of the sequence switch, Fig. 3, and terminal 7 of terminal arc 255 are used. Again relays 311 and 215 are operated upon the establishment of the fundamental circuit. The operation of relay 311 establishes 70 an actuating circuit for sequence switch magnet 300 which may be traced from grounded battery through the winding of sequence switch magnet 300, lower contact of sequence switch spring 328, outer left 75 contact and armature of relay 311 to ground through lower contact of sequence switch spring 322, rotating the sequence switch from position 3 to position 4. The holding circuit for relay 311 is again established 80 upon the movement of the sequence switch from position 3 to position 4 and is the same as previously traced. A circuit is established in sequence switch positions 3 and 4 for trip magnet 303, which may be traced 85 from grounded battery through winding of trip magnet 303, right upper and lower contacts of sequence switch 335 to ground. The energization of the trip magnet causes brushes 350, 351 and 352 to be brought into 90 engagement with the bank terminals in the well known manner of such operation. A circuit is now established for up-drive magnet 302 which may be traced from grounded battery through winding of magnet 302, 95 right upper contact of sequence switch spring 334, left outer contact and armature of relay 311 to ground through lower contact of sequence switch spring 322. The incoming selector switch elevator and commutator brushes are now driven in an upward movement thus causing brush 342 to engage the conducting portion of commutator 345 to establish a shunt for deenergizing stepping relay 215. This shunt path may be 100 traced from ground through lower contact of sequence switch spring 333, brush 342, conducting portion of commutator 345, right upper contact of sequence switch spring 336 to a point of junction in the fundamental circuit where an effective shunt is placed around relay 215.

The initial operation of relay 215 upon the establishment of the fundamental circuit establishes a circuit for operating 115 counting relay 2. This may be traced from ground through the armature and contact of relay 215, brush 201, terminal 7 of terminal arc 250, right contacts of key 133, left outer contacts of key 141, right normal contact and armature of counting relay 2', winding of counting relay 2, fourth right contact and armature of relay 10 to ground 120 battery. The operation of counting relay 2 establishes a holding circuit for itself and an operating circuit for relay 2' which is effective upon the release of relay 215. The release of relay 215, as described, is 125 effective when brush 342 engages the conducting portion of commutator 345.

As the incoming selector switch elevator is driven in an upward movement, brush 342 is intermittently engaged with non-conducting and conducting portions of commutator segment 345 thus causing the intermittent energization and deenergization of stepping relay 215. Counting relays 1, 1', 0, 0', and 11 are thus operated in the well known manner of operating counting relays.

The operation of counting relay 0' opens the fundamental circuit to release relay 311 when brush 342 arrives at the non-conducting portion of commutator segment 345, next above the conducting portion causing the release of relay 215 and the operation of counting relay 0'. The release of relay 311 arrests the upward movement of the incoming selector switch elevator and establishes an energizing circuit for sequence switch magnet 300. The energizing circuit may be traced from grounded battery through the winding of magnet 300, left upper contact of sequence switch spring 328 to ground through left inner armature and contact of relay 311. The sequence switch is thus moved from position 4 to position 5.

In sequence switch position 5 a circuit is again established for actuating relay 311. This may be traced from grounded battery through the left winding of relay 311, right upper and lower contacts of sequence switch spring 327 to ground. The operation of relay 311 establishes a circuit for energizing sequence switch magnet 300 which may be traced from grounded battery through the winding of magnet 300, lower contact of sequence switch spring 328, left outer contact and armature of relay 311 to ground through lower contact of sequence switch spring 322. The sequence switch is thus rotated from position 5 to position 6.

In position 6 the incoming selector switch is seeking an idle trunk to a final selector circuit. A busy final selector circuit is characterized by ground impressed on terminal 353. Assuming that an idle final selector switch has been immediately encountered relay 311 is released.

Since the trunk hunting feature of this incoming selector switch is described in detail in previously referred to Patent 1,395,977, it will be omitted from this description.

The releasing of relay 311 connects a busy ground to terminal 353 to prevent other incoming selectors from stopping on the same terminal. This path may be traced from ground through the right upper contact of sequence switch spring 329, right normal contact and armature of relay 311, right upper and lower contacts of sequence switch spring 330, brush 350 to terminal 353. The release of relay 311 also establishes an actuating circuit for sequence switch magnet 300 which may be traced from grounded battery through winding of magnet 300 left

upper contact of sequence switch spring 328 to ground through left inner armature and contact of relay 311. The sequence switch is thus rotated from position 6 into position 7.

In sequence switch position 7, a circuit is established for operating relay 311, which may be traced from grounded battery through the left winding of relay 311, right upper and lower contacts of sequence switch spring 327 to ground. The operation of relay 311 establishes an energizing circuit for sequence switch magnet 300 which may be traced from grounded battery through the winding of magnet 300, lower contact of sequence switch spring 328, left upper contact and armature of relay 311 to ground through lower contact of sequence switch spring 322. The sequence switch is thus rotated from position 7 to position 8 where it will remain until the final selector switch has completed units selection. In position 8 a circuit is established to hold relay 311 in an operated position. This circuit may be traced from grounded battery through the right winding of relay 311, right upper and lower contacts of sequence switch spring 321, right contact and armature of relay 311, right lower contact of sequence switch spring 321, brush 351, terminal 354, upper left and lower right contacts of sequence switch spring 421, resistance 450, left lower contact of sequence switch spring 419 to ground.

It will be remembered that relay 11 was operated upon the completion of incoming selector switch group selection. The operation of this relay establishes a circuit for energizing switch magnet 200. This may be traced from ground through the armature and contact of relay 11, terminal 7 of terminal arc 252, brush 203, contacts and winding of switch magnet 200 to grounded battery. The switch is thus rotated from terminal 7 to terminal 8 and upon leaving terminal 7 opens the energizing circuit for relay 10. The deenergization of relay 10 causes the deenergization of the counting relays and the release of relay 220. The release of relay 220 establishes an energizing path for switch magnet 200 which may be traced from ground through the armature and contact of relay 220, terminal 8 of terminal arc 252, brush 203, contacts and winding of switch magnet 200 to grounded battery. The switch is thus rotated from terminal 8 to terminal 9 where a circuit is again established for operating relay 10 through terminal 9 of terminal arc 251, brush 202 to ground. The operation of relay 10 establishes an operating circuit for relay 220 as previously traced. The operation of relay 220 establishes an energizing circuit for switch magnet 200 which may be traced from ground through the armature and contact of relay 220, terminal 9 of ter-

55 minal arc 251, brush 203 to contacts and winding of switch magnet 200 to grounded battery. The switch is thus rotated from terminal 9 to terminal 10.

- 56 5 The fundamental is now extended to the final selector switch, Fig. 4. This fundamental circuit may be traced from grounded battery through the left upper contact of sequence switch spring 416, right winding of relay 407, left lower contact of sequence switch spring 418, left lower contact of sequence switch spring 422, terminal 355, brush 352, left upper contact of sequence switch spring 332, resistance 315, right upper contact of sequence switch spring 324, tip spring of jack 304, tip of plug 234, tip conductor of patching cord 233, tip of plug 232, tip spring of jack 231, right outer contact and armature of relay 221, brush 206, terminal 10 of terminal arc 255, left winding of relay 214, winding of relay 215, contact and armature of counting relay 0', right inner normal contact and armature of relay 212, left inner armature and contact of relay 221, ring spring of jack 231, ring of plug 232, ring conductor of patching cord 233, ring of plug 234, ring spring of jack 304, right lower contact of sequence switch spring 323, resistance 316 to ground through right lower contact of sequence switch spring 335. Relay 407 and relay 215 operate upon the establishment of this circuit.

57 Relay 407 in attracting its left armature establishes a circuit for energizing relay 406. This circuit may be traced from grounded battery through the left winding of relay 406, left upper contact of sequence switch spring 417, left contact and armature of relay 407 to ground through left upper contact of sequence switch spring 410. The operation of relay 406 establishes a locking circuit for itself from grounded battery through its left winding, the normal armature and contact of relay 405, left contact and armature of relay 406, terminal 353, brush 350, right lower and left upper contacts of sequence switch 330 to ground. Relay 406 in attracting its right armature establishes an energizing circuit for magnet 400. This may be traced from ground through the right armature and contact of relay 406, lower contacts of sequence switch spring 411, winding of sequence switch magnet 400 to grounded battery. Thus the sequence switch is rotated from position 1 to position 2.

58 Upon the movement of the sequence switch from position 1 to position 2 a holding circuit is established for relay 407 which may be traced from grounded battery through the left upper contact of sequence switch spring 416, right winding of relay 407, lower contact of sequence switch spring 415, right contact and armature of relay 407, right

59 lower contact of sequence switch spring 418, 65 left lower contact of sequence switch spring 422 and thence over the fundamental circuit to ground as previously traced.

60 In sequence switch position 2 a circuit is established for energizing up-drive magnet 403. This may be traced from grounded battery through the winding of magnet 403, right upper contact of sequence switch spring 426, left contact and armature of relay 407 to ground through left upper contact of sequence switch spring 410. The final selector switch elevator is now driven upward to make brush selection and brush 431 is brought into contact with commutator segment 434, thus intermittently establishing 70 a shunt for stepping relay 215. This shunt path may be traced from ground through the right upper contact of sequence switch spring 419, brush 431, commutator segment 434, right upper contact of sequence switch spring 422, to the fundamental circuit.

75 The initial operation of relay 215 over the fundamental circuit establishes an energizing circuit for counting relay 1. This circuit may be traced from ground through the armature and contact of relay 215, brush 201, terminal 10 of terminal arc 250, right contacts of key 141, normal contacts of counting relay 1', winding of counting relay 1, fifth right contact and armature of relay 10 to grounded battery. The operation of counting relay 1 establishes a locking circuit for itself and an operating circuit for relay 1' which is effective upon the first release of stepping relay 215 when the shunt is established. Counting relays 0, 0' and 11 will be operated in the well known manner of operating counting relays. The operation of counting relay 0' opens the fundamental circuit which will cause the release of relay 407, when brush 431 moves upward to a non-conducting portion of commutator segment 434.

80 100 The release of relay 407 arrests the upward movement of the selector switch elevator and establishes an energizing circuit for sequence switch magnet 400. This energizing circuit may be traced from grounded battery through the winding of magnet 400, 115 right upper contact of sequence switch spring 413, left normal contact and armature of relay 407 to ground through left upper contact of sequence switch spring 410. The sequence switch is thus rotated from 120 position 2 to position 3.

125 The operation of counting relay 11 establishes an actuating circuit for switch magnet 200 which may be traced from ground through the armature and contact of counting relay 11, terminal 10 of terminal arc 252, brush 203, contacts and winding of switch magnet 200 to grounded battery thus

- rotating the switch from terminal 10 to terminal 11. The stepping of brush 202 from terminal 10 to terminal 11 opens the energizing circuit for relay 10 which releases. 5 The release of relay 10 deenergizes the counting relays that have been operated and also deenergizes relay 220. The deenergization of relay 220 establishes a circuit for energizing switch magnet 200 which may be traced from ground through the armature and contact of relay 220, terminal 11 of terminal arc 252, brush 203, contacts and winding of switch magnet 200 to grounded battery thus rotating the switch from terminal 11 to terminal 12.

Brush 202 in contact with terminal 12 of terminal arc 251 establishes an actuating circuit for relay 10 the same as previously traced. Relay 10 in attracting its right 20 armatures connects grounded battery to the windings of the counting relays and in attracting its left armatures establishes an obvious operating circuit for relay 220. The operation of relay 220 establishes an actuating circuit for switch magnet 200 which may be traced from ground through the armature and contact of relay 220, terminal 12 of terminal arc 252, brush 203, contacts and winding of switch magnet 200 to 25 grounded battery, thus rotating the switch from terminal 12 to terminal 13 where the fundamental circuit is again established for tens selection of the final selector switch.

It will be remembered that the sequence switch of the final selector, Fig. 4, is resting in position 3. Therefore, upon the closure of the fundamental a circuit is established for operating relay 407 and relay 215. This may be traced from grounded battery 30 through left upper contact of sequence switch spring 416, right winding of relay 407, left lower contact of sequence switch spring 418, left lower contact of sequence switch spring 422 and thence over the fundamental through the winding of relay 215 to ground at sequence switch spring 335 as previously traced. The operation of relay 407 establishes an actuating circuit for sequence switch magnet 400 which may be traced from grounded battery through the winding of sequence switch magnet 400, lower contact of sequence switch spring 413, left contact and armature of relay 407 to ground through upper contact of sequence switch spring 410. The sequence switch is thus rotated from position 3 to position 4 and in rotating to position 4 the holding circuit for relay 407 is established as previously traced. 55 In sequence switch position 3 and 4 an obvious circuit is established for energizing the trip magnet 404 to cause the actuation of the tripping spindle in the well known manner. Brushes 437, 438 and 439 are now 60 prepared to engage the bank terminals upon

the subsequent upward movement of the selector switch elevator.

Upon the forward movement of the sequence switch into position 4, a circuit is established for the high speed up-drive magnet 403. This may be traced from grounded battery through the winding of magnet 403, right upper contacts of sequence switch spring 426, left contact and armature of relay 407 to ground through upper contact of sequence switch spring 410. The selector switch elevator is thus driven in an upward movement to bring brush 432 into engagement with commutator segment 435. The engagement of this brush with the conducting portion of commutator segment 435 establishes a shunt circuit effective for releasing stepping relay 215. This shunt path may be traced from ground through the left upper contact of sequence switch spring 419, brush 432, conducting portion of commutator segment 435, right upper contact of sequence switch spring 418, left lower contact of sequence switch spring 432 and thence over the fundamental circuit causing the release of relay 215. 80

The initial actuation of stepping relay 215 establishes a circuit for operating counting relay 9 which may be traced from ground through the armature and contact of relay 215, brush 201, terminal 13 of terminal arc 250, right contacts of key 159, normal armature and contact of counting relay 9', winding of counting relay 9, first right contact of relay 10 to grounded battery. The operation of counting relay 9 establishes a holding circuit for itself and an operating circuit for counting relay 9' which is effective upon the first release of stepping relay 215. Upon the upward movement of the final selector switch elevator, brush 432 is intermittently engaged with the conducting and non-conducting portions of commutator segment 435, intermittently operating and releasing stepping relay 215. The counting relays are energized from the intermittent energization and deenergization of stepping relay 215 in the well known manner of operating counting relays until all of the counting relays including counting relay 0' 95 and relay 11 have been energized. 100

The operation of counting relay 0' opens the fundamental circuit to cause the release of relay 407 as soon as the shunt ground is removed at commutator 435. The release of relay 407 arrests the upward movement of the final selector switch elevator and establishes a circuit for energizing sequence switch magnet 400. This energizing circuit may be traced from grounded battery through the winding of magnet 400, right upper contact of sequence switch spring 413, left normal contact and armature of relay 407 to ground through upper contact of sequence switch spring 410. The sequence 115 120 125

switch is thus rotated from position 4 to position 5 where it awaits further action of the control circuit.

The operation of counting relay 11 establishes a circuit for actuating switch magnet 200 which may be traced from ground through the armature and contact of counting relay 11, terminal 13 of terminal arc 252, brush 203, contacts and winding of switch magnet 200 to grounded battery. The switch is thus rotated from terminal 13 to terminal 14, opening the energizing circuit for relay 10. The release of relay 10 removes the operating battery from the counting relays, causing their release. The release of relay 10 also opens the energizing circuit for relay 220 causing its release. The release of relay 220 establishes a circuit for energizing switch magnet 200 which may be traced from ground to the armature and contact of relay 220, terminal 14 of terminal arc 252, brush 203, contacts and winding of switch magnet 200 to grounded battery. The switch is thus rotated from terminal 14 to terminal 15 where the operating circuit for relay 10 is re-established as previously traced. The operation of relay 10 connects grounded battery to the windings of the counting relay and establishes an obvious energizing circuit for relay 220. Relay 220 in attracting its armature establishes a circuit for energizing switch magnet 200 which may be traced from ground through the armature and contact of relay 220, terminal 15 of terminal arc 252, brush 203, contacts and winding of switch magnet 200 to grounded battery. The switch is thus rotated, from terminal 15 to terminal 16 to reestablish the fundamental circuit for final units selection.

It will be remembered that the sequence switch in the final selector, Fig. 4, is standing in position 5. A circuit is now established for energizing relay 407 and relay 215 over the fundamental circuit to cause units selection to take place. This energizing circuit may be traced from grounded battery through the left upper contact of sequence switch spring 416, right winding of relay 407, left lower contact of sequence switch spring 418, left lower contact of sequence switch spring 422, and thence over the fundamental circuit through the winding of relay 215 to ground at sequence switch spring 335, as previously traced. Relay 407, in energizing, establishes an energizing circuit for sequence switch magnet 400 which may be traced from grounded battery through the winding of magnet 400, lower contact of sequence switch spring 413, left contact and armature of relay 407 to ground through upper contact of sequence switch spring 410. The sequence switch is thus rotated from position 5 to position 6 and in rotating to position 6 establishes a

holding circuit for relay 407 as previously traced.

In sequence switch position 6 an energizing circuit is established for slow speed up-drive magnet 402. This may be traced from grounded battery through the winding of magnet 402, lower contact of sequence switch spring, 417, left contact and armature of relay 407 to ground through upper contact of sequence switch spring 410. The final selector switch elevator is now driven upward causing the upward movement of brush 431 in contact with commutator segment 434. Since the final selector switch is directed to the first or zero terminals in a group of ten, the shunt path for deenergizing stepping relay 215 is immediately established to cause the energization of counting relays 0' and 11. This shunt path may be traced from ground through the left upper contact of sequence switch spring 419, brush 431, conducting portion of commutator segment 434, right upper contact of sequence switch spring 422 to a junction joint in the fundamental circuit effective for maintaining relay 407 in operated position and releasing stepping relay 215.

The initial operation of relay 215 establishes the above mentioned energizing circuit for counting relay 0. This may be traced from ground through the armature and contact of relay 215, brush 201, terminal 16 of terminal arc 250, left contacts of key 160, winding of counting relay 0, fifth right contact and armature of relay 10 to battery. The operation of counting relay 0 establishes a holding circuit for itself and an operating circuit for counting relays 0' and 11 which is effective upon the release of stepping relay 215.

The operation of counting relay 0' opens the fundamental circuit to cause the release of relay 407 which becomes effective as soon as brush 431 is elevated to a non-conducting portion of commutator segment 434. The release of relay 407 arrests the upward movement of the selector switch elevator and establishes an energizing circuit for the sequence switch magnet 400. This energizing circuit may be traced from grounded battery through the winding of magnet 400, right upper contact of sequence switch spring 413, left normal contact and armature of relay 407 to ground through upper contact of sequence switch spring 410. The sequence switch is thus rotated out of position 6 and into position 9 under the control of the sequence switch magnet contact.

The operation of counting relay 11 establishes an energizing circuit for switch magnet 200 which may be traced from ground through the armature and contact of counting relay 11, terminal 16 of terminal arc 252, brush 203, contacts and winding of switch magnet 200 to grounded battery.

The switch is thus rotated from terminal 16 to terminal 17, opening the energizing circuit for relay 10. The deenergization of relay 10 opens the energizing circuit for the 5 counting relays causing them to be released and also opens the energizing circuit for relay 220 causing its release. The deenergization of relay 220 establishes an energizing circuit for switch magnet 200 which may be traced from ground through the armature and contact of relay 220, terminal 17 of terminal arc 252, brush 203, contacts and winding of switch magnet 200 to grounded battery. The switch is thus rotated from 10 terminal 17 to terminal 18. Brush 206 in contact with terminal 18 of terminal arc 255 establishes the fundamental circuit previously traced. The switch will now remain in position 18 to further control the incoming selector switch, Fig. 3, as will be described later.

It will be remembered that the release of relay 407 rotated the final selector sequence switch into position 9. In this position of 25 the sequence switch a circuit is established for operating relay 407. This may be traced from grounded battery through the left upper contact of sequence switch spring 416, right winding of relay 407, lower right and 30 upper left contacts of sequence switch spring 415 to ground through right contact and armature of relay 406. The operation of relay 407 establishes an energizing path for sequence switch magnet 400 which may be traced from grounded battery through 35 the winding of magnet 400, lower contact of sequence switch spring 413, left contact and armature of relay 407 to ground through upper contact of sequence switch spring 410. The sequence switch is thus rotated out of position 9 and into position 12 under the control of the sequence switch magnet contact.

In position 12 of the final selector sequence 45 switch, the line is tested to determine whether it is in a busy or idle condition. Since there are a number of testing devices the same as that shown in Fig. 5, connected to adjacent line terminals the P. B. X. hunting feature of the final selector switch is 50 employed to connect the final selector switch to an idle one of these testing devices. Busy line terminals connected to a testing device are characterized by grounded battery connected to terminal 440 derived from a final 55 selector switch the same as Fig. 4. This may be traced from grounded battery through the right upper contact of sequence switch spring 416, resistances 424 and 423, lower contacts of sequence switch spring 420, brush 437 to terminal 440. An idle line connected to a testing device is characterized by ground connected to terminal 440 through the winding of relay 505 and the 60 upper contact of sequence switch spring 520.

Assuming that the first line connected to a testing device is busy a circuit is established for holding relay 407 actuated. This circuit may be traced from grounded battery in a circuit the same as that shown in Fig. 4, 70 through right upper contact of sequence switch spring 416 resistances 424 and 423, lower contacts of sequence switch spring 420, brush 437, contact 440 to brush 437 in the final selector switch now being described, through right lower and upper contacts of sequence switch 420, right armature and contact of relay 407, right upper contact of sequence switch spring 415, right winding of relay 407, left lower contact of sequence switch spring 418, left upper contact of sequence switch spring 422, winding of relay 405 to ground. Relay 405 does not receive sufficient current to operate in the circuit just traced since it is in multiple with the winding of relay 505 which is of low resistance. 85

With relay 407 held in an operated position to grounded battery in the busy connection, an energizing circuit for slow speed up-drive magnet 402 is established. This energizing circuit may be traced from grounded battery through the winding of magnet 402, lower contact of sequence switch spring 417, left contact and armature of relay 407 to ground through the upper contact of sequence switch spring 410. The final selector switch elevator is now driven in an upward movement until brush 437 is brought into engagement with a line connected to an idle testing device characterized by ground connected to terminal 440. The holding circuit for relay 407 is thus opened to cause its release. Relay 407 in releasing opens the energizing circuit for up-drive magnet 402 thus arresting the upward movement of the final selector switch elevator. The release of relay 407 also establishes an energizing circuit for sequence switch magnet 400 which may be traced from grounded battery through the winding of magnet 400, right upper contact of sequence switch spring 413, left normal contact and armature of relay 407, left lower contact of sequence switch spring 410 to ground through right contact and armature of relay 406. The sequence switch is thus rotated from position 12 to position 13. 105

In sequence switch position 13 a circuit is established for sequence switch magnet 400 which may be traced from grounded battery through the winding of magnet 400, lower contacts of sequence switch spring 411 to ground through right contact and armature of relay 406 thus rotating the sequence switch to position 14 where a circuit is again established for actuating sequence switch magnet 400. This may be traced from grounded battery through winding of magnet 400, right upper contact of sequence 110 115 120 125 130

switch spring 413, left normal contact and armature of relay 407 to ground through upper contact of sequence switch spring 410. The sequence switch is thus rotated from 5 position 14 to position 15 where it will remain until the incoming selector, Fig. 3, has been tested.

It will be remembered that the incoming selector switch remained in position 8 during the control of the final selector switch. During this time relay 311 remained actuated over a path traced from grounded battery through right winding of relay 311, right upper and lower contacts of sequence switch spring 321, right contact and armature of relay 311, right lower contact of sequence switch spring 331, brush 351, terminal 354, upper left and lower right contacts of sequence switch spring 421, resistance 450, 15 left lower contact of sequence switch spring 419 to ground. This holding circuit for relay 311 was opened when the final selector sequence switch rotated from position 8 to 9 as previously described and at this time relay 311 is deenergized to establish an energizing circuit for sequence switch magnet 300. This energizing circuit may be traced from grounded battery through the winding of magnet 300, left upper contact of sequence switch spring 328, left inner armature and contact of relay 311 to ground. The incoming selector sequence switch 300 is thus rotated from position 8 to position 9.

In position 9 of the incoming selector 35 sequence switch battery and ground is reversed with relation to the fundamental circuit. This is done to signal the controlling circuit, Fig. 2, when final selections have been completed and relay 311 released. 40 This fundamental circuit may be traced from grounded battery through the right winding of relay 311, lower contacts of sequence switch spring 325, resistance 316, lower contact of sequence switch spring 323, 45 ring spring of jack 304, ring of plug 234, ring conductor of patching cord 233, ring of plug 232, ring spring of jack 231, left inner contact and armature of relay 221, left inner normal armature and contact of relay 50 212, contact and armature of counting relay 0', winding of stepping relay 215, left winding of polarized relay 214, terminal 18 of terminal arc 255, brush 206, left outer armature and contact of relay 221, tip spring of 55 jack 231, tip of plug 232, tip conductor of patching cord 233, tip of plug 234, tip spring of jack 304, upper contact of sequence switch spring 324, resistance 315, left lower and upper contacts of sequence switch 60 336, upper contacts of sequence switch spring 330 to ground. Relays 311, 215 and 214 are operated in this circuit.

The operation of relay 214 establishes an actuating path for relay 216 and a locking circuit for itself which may be traced from

ground through brush 204, terminal arc 253, contact and armature of relay 214, through the windings of relays 214 and 216 in multiple to grounded battery. Relay 216 upon attracting its right outer armature establishes a circuit for lamp 230 to indicate the progress of the test to the test man. The circuit for lighting lamp 230 may be traced from grounded battery through resistances 225, lamp 230, right outer contact and armature of relay 216, terminal 18 of terminal arc 251, brush 202 to ground. Relay 216 in attracting its left armature establishes a circuit for operating counting relay 0. This circuit may be traced from ground through the armature and contact of stepping relay 215, brush 201, terminal 18 of terminal arc 250, left contact and armature of relay 216, winding of counting relay 0, fifth right contact and armature of relay 10 to grounded battery. It will be noted that relay 10 is actuated from ground at brush 202. The operation of counting relay 0 establishes a locking circuit for itself and an operating circuit for counting relays 0' and 11 which is effective upon the release of relay 215. Relay 215 while operated maintains a shunt ground around the windings of counting relays 0' and 11. Relay 215 is released upon further rotation of the incoming selector sequence switch as will be described.

The operation of relay 311, as described upon the closure of the fundamental, establishes a circuit for actuating relay 310. This may be traced from grounded battery through the winding of relay 310, right upper contact of sequence switch spring 326, right contact and armature of relay 311, upper contacts of sequence switch spring 326, right contact and armature of relay 311, upper contacts of sequence switch spring 330 to ground. The operation of relay 310 establishes an actuating circuit for sequence switch magnet 300 which may be traced from grounded battery through the winding of magnet 300, contact and armature of relay 310, left lower and upper contacts of sequence switch spring 330 to ground. The sequence switch is thus rotated from position 9 to position 10 thereby opening the fundamental circuit to cause the release of relay 215. Counting relays 0' and 11 are now operated from ground through the armature and control of counting relay 0, windings of counting relays 0' and 11, to grounded battery through the fifth right contact and armature of relay 10. The operation of counting relay 0' causes the fundamental circuit to remain open until the control circuit, Figs. 1 and 2, can adjust itself to further control the incoming selector, Fig. 3. The operation of counting relay 11 establishes a circuit for energizing switch magnet 200 which may be traced from ground through the armature and contact 130

of counting relay 11, terminal 18 of terminal arc 252, brush 203, contacts and winding of switch magnet 200 to grounded battery. The switch is thus rotated from terminal 18 to terminal 19 causing the release of relay 10, relay 220 and the counting relays as previously described.

Brush 206 in contact with terminal 19 of terminal arc 255 establishes what is known as trunk closure with relation to the incoming selector switch, Fig. 3. This simulates the connection of the incoming selector switch to a calling subscriber preceding the ringing of the wanted subscriber's station. The circuit establishing trunk closure may be traced from grounded battery through the right winding of relay 311, upper contacts of sequence switch spring 321, resistance 315, upper contact of sequence switch spring 324, tip spring of jack 304, tip of plug 234, tip conductor of patching cord 233, tip of plug 232, tip spring of jack 231, outer contact and armature of relay 221, brush 206, terminal 19 of terminal arc 255 resistance 226, polarized relay 218, left inner normal contact and armature of relay 212, inner armature and contact of relay 221, ring spring of jack 231, ring of plug 232, ring conductor of patching cord 233, ring of plug 234, ring of spring 304, lower contact of sequence switch spring 323, resistance 316 to ground through lower contact of sequence spring 335. Since relay 218 is polarized in the opposing direction to the current flow in the circuit path just traced it will not operate. Relay 311, however, operates to establish an energizing path for sequence switch magnet 300 to rotate the sequence switch into the position for connecting, what is known as, immediate ringing potential to the line. The circuit for actuating relay 310 is reestablished by the operation of relay 311 and the circuit for energizing sequence switch magnet 300 may be traced from grounded battery through the winding of magnet 300, contact and armature of relay 310, left lower and upper contacts of sequence switch spring 330 to ground. The sequence switch is thus rotated from position 10 to position 11.

In sequence switch position 11, relay 311 is held in an operated position over the circuit traced from grounded battery through the left winding of relay 311, armature and contact of relay 314, left upper contact of sequence switch spring 334, left outer contact and armature of relay 311, upper contact of sequence switch spring 322, sleeve of jack 304, sleeve of plug 234, sleeve of conductor of patching cord 233, sleeve of plug 232, sleeve of jack 231, brush 205, terminal 19 of terminal arc 254, winding of relay 219, coil 257, to ground through terminal arc 253 and brush 204.

65 Coil 257 is of low resistance and coil 258

is of high resistance thus forming a potentiometer so that relay 219 will operate from either grounded battery or ground connected to the sleeve of jack 304. Relay 219 therefore, operates upon the rotation of switch 200 to terminal 19 and remains operated during the remainder of time that the incoming selector switch, Fig. 3, is being tested. The operation of relay 219 establishes a circuit for energizing the winding of relay 210. This circuit is obvious and need not be traced. The operation of relay 210 establishes a circuit for lighting lamp 227 from grounded battery through resistance 222, right outer contact and armature of relay 210, lamp 227, contact and armature of relay 218 to ground through left armature and contact of relay 210. The utility of this lamp will be described later.

Preceding position 11 of the incoming selector sequence switch, Fig. 3, the said incoming selector switch has been controlled and tested by the testing device shown in Figs. 1 and 2. In position 11 and further positions of the sequence switch to be described later, the normal function of the incoming selector is to apply ringing potential to the line conductors to ring the bell at a subscriber's station and remove said ringing potential immediately upon the removal of the receiver from the subscriber's station switchhook. Fig. 5 is designed to automatically operate to simulate the subscriber's station including the removal of the receiver from the switchhook.

The testing device shown in Fig. 5 is started in its operation by the application of ringing potential and ringing ground from the incoming selector and from that point it automatically applies test to the incoming selector apparatus. As the incoming selector progressively operates it must respond to these tests if its apparatus is in correct adjustment.

Ringing ground is applied to the tip conductor of the incoming selector, Fig. 3, at the right upper contact of sequence switch spring 332 establishing a circuit for operating relay 506. This may be traced from ringing ground through the right upper contact of sequence switch spring 332, brush 352, terminal 355, lower contacts of sequence switch spring 422, brush 439, terminal 442, conductor 502, left upper contact of sequence switch spring 529, left winding of relay 506 to grounded battery. The operation of relay 506 establishes a circuit for energizing sequence switch magnet 500 which may be traced from grounded battery through the winding of magnet 500, left upper contact of sequence switch spring 524 to ground through left contact and armature of relay 506. The sequence switch is thus rotated from position 1 to position 2 and from position 2 to position 3 under the control

of the sequence switch magnet contact. The operation of relay 506 indicates that ringing ground is properly connected at the incoming selector switch. It will be noted that sequence switch 500 in rotating from position 1 to position 2 opens the actuating circuit for relay 506 causing its release.

In position 1 of sequence switch 500 a circuit is also established for operating relay 507 from the immediate ringing potential. This circuit may be traced from ringing potential through the left lower contact of sequence switch spring 320, winding of relay 314, lower contacts of sequence switch spring 321, right contact and armature of relay 311, right lower contact of sequence switch spring 331, brush 351, terminal 354, upper contacts of sequence switch spring 421, brush 438, terminal 441, conductor 502, condenser 550, winding of relay 507, right upper contact of sequence switch spring 520 to ground. As previously described, relay 506 released between sequence switch positions 1 and 2, a circuit is however, established in position 2 for reoperating relay 506 which may be traced from grounded battery through the left winding of relay 506, upper contact of sequence switch spring 527, contact and armature of relay 507, right lower contact of sequence switch spring 529, conductor 502 and thence to ringing ground at sequence switch spring 332 over the circuit previously traced. As sequence switch 500 rotates out of position $2\frac{1}{4}$ a holding circuit for relay 506 is established from grounded battery through the left winding and right contact and armature of relay 506, left lower contact of sequence switch spring 527, contact and armature of relay 507, right lower contact of sequence switch spring 529, conductor 502 and thence to the ringing ground at incoming sequence switch spring 332. Relays 506 and 507 remain operated during the period of application of the immediate ringing potential. It will be noted that the sequence switch is rotated from position 1 to position 3 and that during the time of this rotation, relay 507 must operate from the ringing potential to establish the described circuit for operating and holding relay 506. Therefore, when sequence switch 500 arrives in position 3 the holding circuit for relay 506 is the only established means for maintaining this relay in an operated position. The test of the application of immediate ringing is made in the manner described so that the testing device will remain in position 3 if said immediate ringing potential is not impressed upon the line and the fact that the testing device remains in position 3 indicates this to the test-man.

The immediate ringing potential is connected to the line during the period of time controlled by interrupter 307 in sequence

switch positions 11 and 12 of the incoming selector switch. The operation of interrupter 307 rotates the incoming selector sequence switch from position 11 to position 13. This circuit may be traced upon the first operation of interrupter 307 in position 11 from ground through the interrupter contact 337, left upper contact of sequence switch spring 326, winding of relay 310 to battery operating relay 310. The operation of relay 310 establishes an actuating circuit for sequence switch magnet 300 which may be traced from grounded battery through the winding of magnet 300, contact and armature of relay 310 to ground through left lower and upper contacts of sequence switch spring 330. The sequence switch is rotated from position 11 to position 12 and in thus rotating opens the energizing circuit for relay 310 causing its release. The subsequent operation of interrupter 307 establishes a circuit for moving the sequence switch from position 12 to position 13. This may be traced from ground through the contact 347 of interrupter 307, lower contact of sequence switch spring 326, winding of relay 310 to grounded battery again operating relay 310. The operation of relay 310 establishes an energizing circuit for sequence switch magnet 300 which may be traced from grounded battery through the winding of magnet 300, contact and armature of relay 310 to ground through the left lower and upper contacts of sequence switch spring 330. As the sequence switch rotates out of position 12 the immediate ringing potential is opened at the left lower contact of sequence switch spring 320. The energizing circuit for relay 310 is also opened causing its release.

Relay 314 is termed the ringing relay, its purpose being to disconnect the ringing current when the receiver is removed from the switchhook at the subscriber's station. It, therefore, should not operate during the time that the ringing potential is carried through its winding for the purpose of ringing the bell at the subscriber's station. It will be noted in the testing features herein-after described that false operation of relay 314 will cause the testing device, Fig. 5, to be arrested in its progression.

During the period of immediate ringing, it will be remembered that relays 506 and 507 are held in an operated position. Relay 506 in attracting its left armature establishes a circuit for rotating sequence switch 500 from position 3 to position 4. This circuit may be traced from grounded battery through the winding of magnet 500, upper contact of sequence switch spring 524, left contact and armature of relay 506 to ground. In position 4 a circuit is established for operating relay 509. This may be traced from grounded battery through the contact of se-

quence switch spring 526, winding of relay 509, right normal contact and armature of relay 510, lower contact of sequence switch spring 524, left contact armature of relay 506 to ground. The operation of relay 509 establishes a locking circuit for itself through its right inner contact and armature to ground, through the left inner contact and armature of relay 511. Relay 509 in operating does not establish any other effective circuit at this time. Upon the termination of the immediate ringing period relays 506 and 507 are released. The release of relay 506 establishes a circuit for operating relay 510. This may be traced from ground through the left normal contact and armature of relay 506, upper contact of sequence switch spring 525, left outer armature and contact of relay 509, winding of relay 510, contact of sequence switch spring 526 to grounded battery. Relay 510 in operating establishes a locking circuit for itself through its left inner contact and armature to ground through right contact and armature of relay 512. The operation of relay 510 does not establish any other effective circuit at this time.

The test of the immediate ringing has now been completed and the apparatus in the testing device, Fig. 5, is positioned to proceed with further tests. This indicates correct adjustment of the apparatus tested. The immediate ringing is used in the normal functioning of this type of incoming selector circuit to immediately ring the subscriber's bell when the incoming selector and final selector are connected to a subscriber's line. After a time interval this immediate ringing potential is replaced by ringing potential applied to the line through the commutator segment of an interrupter. The interrupted ringing current remains connected to the line conductors until such time as the receiver is removed from the switchhook or the calling party disconnects. A number of calls are established preceding the application of the interrupted ringing.

In position 13 of the incoming selector sequence switch, interrupted ringing potential and ringing ground is applied to the line, and a circuit is established for again operating relay 507 of the testing device positioned in sequence switch position 4. This path may be traced from ringing potential through conducting segments of interrupter 306, right lower contact of sequence switch spring 320, relay 314, lower contacts of sequence switch spring 321, right contact and armature of relay 311, right lower contact of sequence switch spring 331, brush 351, terminal 354, upper contacts of sequence switch spring 421, brush 438, terminal 441, conductor 503, condenser 550, winding of relay 507 to ground through right upper contact of sequence switch spring 530. The

operation of relay 507 establishes a circuit for operating relay 506 which may be traced from ringing ground through the right upper contact of sequence switch spring 332, brush 352, terminal 355, lower contacts of sequence switch spring 422, brush 439, terminal 442, conductor 502, right lower contact of sequence switch spring 529, armature and contact of relay 507, left outer contact of sequence switch spring 527, winding of relay 506 to grounded battery. The operation of relay 506 establishes a circuit for operating relay 511 which may be traced from grounded battery through the contact of sequence switch spring 526, winding of relay 511, left outer normal contact and armature of relay 512, right contact and armature of relay 510, lower contact of sequence switch spring 524, to ground through left contact and armature of relay 506. It will be noted that the operation of relay 511 causes the release of relay 509. Relays 506 and 507 remain operated during the period of time that interrupter 306 is rotated with the conducting segment connected to the contact of sequence switch spring 320. At the end of this period of time, relays 506 and 507 release, establishing a circuit for rotating sequence switch 500 from position 4 to position 5.

The foregoing operation and release of relays 506 and 507 is to prepare the testing circuit, Fig. 5, to move its sequence switch into testing position 5 with assurance that the test may be made when the conducting segment of interrupter 306 is first connected to the contact of sequence switch spring 320. In this manner the full time period of ringing is connected to testing device. As is well known in the art, sequence switch 300 may move into position 13 at a time when interrupter 306 has partly rotated over the conducting portion of its segment with relation to the contact of sequence switch spring 320.

The circuit established for rotating sequence switch 500 into position 5 may be traced from grounded battery through the winding of magnet 500, lower contact of sequence switch spring 535, left outer contact and armature of relay 511, left outer normal contact and armature of relay 509, upper contact of sequence switch spring 525, left normal contact and armature of relay 506 to ground. The sequence switch in rotating from position 4 to 5 opens the holding circuit for relays 510 and 511 causing their release.

With sequence switch 500 in position 5, the testing device is prepared to make a test for premature or false operation of the ringing relay 314, and since the time interval for moving sequence switch 500 from position 4 to position 5 is of shorter duration than the time occupied by interrupter 306 for

moving from one conducting segment to the next, this premature operation test will take place when said next conducting segment of interrupter 306 is connected to the contact of sequence switch spring 320. This premature operation test will also be known in this description as a premature tripping test.

Ringing potential from interrupter 306 now establishes a circuit for operating relay 507. This may be traced from ringing potential through the conducting portion of interrupter 306, left lower contact of sequence switch spring 320 and thence to conductor 503 of Fig. 5 as previously traced, thence through condenser 550, winding of relay 507, left upper contact of sequence switch spring 530, conductor 502 and thence to ringing ground at sequence switch spring 332 over the path previously traced. The operation of relay 507 establishes a circuit for operating relay 506 which may be traced from grounded battery through the left winding of relay 506, upper contact of sequence switch spring 527, contact and armature of relay 507 to ground through right upper contact of sequence switch spring 521. The operation of relay 506 establishes a circuit for energizing sequence switch magnet 500 which may be traced from grounded battery through the winding of magnet 500, upper contact of sequence switch spring 524 to ground through left contact and armature of relay 506. The sequence switch is thus rotated from position 5 to position 6 and in rotating from position 5 to position 6 opens the circuit traced for operating relay 506. This relay, however, in position 6 is connected to interrupter 551 and is operated and released upon each rotation of this interrupter. Its operating path may be traced from grounded battery through the left winding of relay 506, left lower contact of sequence switch spring 534, conducting segment of interrupter 551 to ground through the right lower contact of sequence switch spring 528. Upon the first operation of relay 506 under the control of interrupter 551, a circuit is established for operating relay 509. This circuit may be traced from grounded battery through the contact of sequence switch spring 526, winding of relay 509, right normal contact and armature of relay 510, lower contact of sequence switch spring 524, to ground through left contact and armature of relay 506. Relay 509 establishes a locking path for itself to ground at the right normal armature of relay 512. When interrupter 551 rotates to a non-conducting portion of the segment, relay 506 is released establishing a circuit for energizing relay 510. This energizing circuit may be traced from grounded battery through the contact of sequence switch spring 526, winding of relay 510, left outer

contact and armature of relay 509, upper contact of sequence switch spring 525 to ground through left normal contact and armature of relay 506. Relay 510 establishes an obvious locking circuit for itself 70 which need not be traced and also in attracting its left outer armature establishes a circuit for the premature tripping test which is effective upon the subsequent operation of relay 506. The second operation 75 of relay 506 under the control of interrupter 551 establishes a circuit for making the premature trip test upon ringing relay 314. The circuit established for making this premature trip test is of such value in resistances that the test of the adjustment of relay 314 is more severe than is encountered in actual service. This circuit may be traced from ringing potential through the conducting segment of interrupter 306, right lower and upper contacts of sequence switch spring 320, winding of relay 314 and thence over the path previously traced to conductor 503 in Fig. 5, through resistances 560, 561, 562 and 563, lower contact of sequence switch 80 spring 531, right normal contact and armature of relay 511, left outer armature and contact of relay 510, upper contact of sequence switch spring 533 and thence over conductor 502 to ringing ground at sequence 85 switch spring 332 as previously traced.

During the period of time that relay 506 is held in an operated position for the premature trip test, a circuit is established for operating relay 511. This may be traced from grounded battery through the contact of sequence switch spring 526, winding of relay 511, left outer normal contact and armature of relay 512, right contact and armature of relay 510, lower contact of sequence switch spring 524 to ground through left contact and armature of relay 506. The operation of relay 511 opens the holding circuit for relay 509 causing its release. The operation of relay 511 also opens the circuit 100 through which the premature trip test is being applied to ringing relay 314.

One premature trip test has now been completed. This is the first of three premature trip tests that are made during the automatic progression of the testing device, Fig. 5. The advantage of making three premature trip tests is in the probability that each one of these tests will start at a different point in the alternating current wave 115 and thus in one or more of these tests the alternating current is connected through the winding of relay 314 when the current wave is at its peak value. In this manner the maximum surge of current is sent through 120 the winding of relay 314 upon the application of the premature trip test.

It will be remembered that during the first premature trip test, relay 506 operated twice under the control of interrupter 551 125

and that during its second operation relay 511 opens the premature trip test. It is now necessary to count off sufficient time to allow interrupter commutator 306 to rotate 5 through the full ringing period and thence into the silent period or nonconducting portion of the interrupter before advancing the sequence switch, Fig. 5, into the sequence switch position for the next premature trip 10 test. Relays 509, 510, 511 and 512 are used in conjunction with relay 506 and interrupter 551 to count this allotted time. The second release of relay 506 establishes an operating circuit for relay 512. This may 15 be traced from grounded battery through the contact of sequence switch spring 526, winding of relay 512, upper contact of sequence switch spring 525, left outer contact and armature of relay 511, left outer normal contact and armature of relay 509, upper contact of sequence switch spring 525 to ground through normal contact and armature of relay 506. The operation of relay 512 opens the holding circuit for relay 20 510 causing its release. A third operation of relay 506 under the control of interrupter 551 reoperates relay 509 over the circuit previously described for operating this relay. A third release of relay 506 establishes a 25 circuit for operating relay 510 as previously traced. A fourth operation of relay 506 establishes a circuit for rotating sequence switch 500 from position 6 to position 7. This circuit may be traced from grounded 30 battery through the winding of magnet 500, lower contact of sequence switch spring 523, left outer contact and armature of relay 512, right contact and armature of relay 510, lower contact of sequence switch spring 524, 35 to ground through left contact and armature of relay 506. The movement of the sequence switch from position 6 to position 7 releases relays 506, 509, 510, 511 and 512.

It will be noted that the testing device, 40 Fig. 5, is connected in sequence switch position 7 the same as position 5 and thus the sequence switch is rotated from position 7 to position 8 in the same manner as from position 5 to position 6.

In position 8 the second premature trip test is made in the same manner as described in position 6 and the sequence switch is rotated to position 9 upon the completion 45 of the second premature trip test at the termination to the allotted time allowed for the operation of relays 509, 510, 511 and 512.

In position 9 of sequence switch 500 the action is the same as in positions 5 and 7. Relay 507 is operated from the ringing potential and relay 506 from the local circuit path previously traced to rotate sequence switch 500 from position 9 to position 10.

In position 10 of sequence switch 500 the 50 third premature trip test is made in the

same manner as described for the first premature trip test in sequence switch position 6 and at the termination of the third premature trip test the sequence switch 500 is rotated from position 10 to position 11. 70

It will be noted that if relay 314 had operated to disconnect the ringing current during any of the three premature trip tests, the testing device, Fig. 5, would be arrested in its progression and thus indicate that 75 relay 314 is not in proper adjustment.

Relay 507 is again bridged across conductors 502 and 503 in position 11 of sequence switch 500 and will be operated from ringing potential when interrupter 306 rotates to the next succeeding conducting portion of its commutator segment. The operating circuit for relay 507 from the ringing potential is the same as previously traced for its operation. A circuit is now established for actuating relay 506 which may be traced from grounded battery through the left winding of relay 506, upper contact of sequence switch spring 527, contact and armature of relay 507 to ground through right 80 upper contact of sequence switch spring 521. A circuit is now established for rotating sequence switch 500 from position 11 to position 12. This circuit may be traced from grounded battery through the winding of magnet 500, upper contact of sequence switch spring 524 to ground through the left contact and armature of relay 506. 85

A test is now made of the tripping or operating adjustment of ringing relay 314. 100 This is done automatically by the testing device, Fig. 5, in position 12 of the sequence switch through resistances bridging the tip and ring conductor for a limited time interval. The resistances are of such value 105 that the more severe test of the operating adjustment of ringing relay 314 is made than would be encountered in actual service. The feature of limiting the time that the tripping test is applied is for the purpose 110 of locating ringing relays that are sluggish in their action. A requirement in service maintenance is that the ringing potential be disconnected immediately upon removal of the receiver from the switchhook. This requirement is to prevent the ringing potential 115 being tripped subsequent to the called party placing the receiver to the ear.

It will be noted that relay 506 is again under the control of interrupter 551 in sequence switch position 12. The first operation of relay 506 establishes a circuit for operating relay 509 as previously traced. The subsequent release of relay 506 establishes a circuit for operating relay 510, as 120 previously traced. The operation of relay 510 establishes a circuit for bridging resistances 560 and 561 across the line to tip of ringing relay 314. This circuit may be 125 traced from ringing potential through the 130

- conducting portion of the commutator of interrupter 306, right, lower contact of sequence switch spring 320, ringing relay 314, lower contacts of sequence switch spring 321, 5 right contact and armature of relay 311, right lower contact of sequence switch spring 331, brush 351, terminal 354, upper contacts of sequence switch spring 421, brush 438, terminal 441, conductor 503, resistances 560 and 561, upper contact of sequence switch spring 531, right normal contact and armature of relay 511, left outer contact and armature of relay 510, upper contact of sequence switch spring 533, conductor 502, 10 terminal 442, brush 439, lower contacts of sequence switch spring 422, terminal 355, brush 352, to ringing ground through right upper contact of sequence switch spring 332. The ringing relay 314 to be in correct adjustment must operate before interrupter 551 disconnects from its conducting segment. Relay 506 releases through the disconnection of interrupter 551 and the release of relay 509 establishes a circuit for operating 15 relay 511 to open the circuit established for operating the ringing relay 314. The circuit for operating relay 511 is the same as previously traced. The operation of relay 511 opens the holding circuit for relay 509 causing its release. 20 Assuming that relay 314 is in proper adjustment, its operation opens the holding circuit for relay 311 causing its release to open the circuit through which ringing potential is imposed upon the line conductors. The 25 release of relay 311 also establishes a circuit for actuating sequence switch magnet 300. This may be traced from grounded battery through the winding of magnet 300, left upper contact of sequence switch spring 328 to ground through the armature and contact of relay 311. The sequence switch is thus rotated out of position 13 and will continue to rotate to position 16 under the 30 control of the magnet contact. During the time that the sequence switch is rotated through positions 14 and 15 a circuit is established for operating relay 311 which may be traced from grounded battery through the left winding of relay 311 to ground through the right upper and lower contacts of sequence switch spring 327. The 35 operation of relay 311 establishes a locking circuit for itself which may be traced from grounded battery through its left winding, lower contact of sequence switch spring 334, left outer contact and armature of relay 311, upper contact of sequence switch spring 322, sleeve of jack 304, sleeve of plug 234, sleeve 40 conductor of patching cord 233, sleeve of plug 232, sleeve of jack 231, brush 205 and terminal 19 of terminal arc 254, winding of relay 219, to ground through terminal arc 253 and brush 204. Relay 311 remains operated over the path traced until the testing 45 control circuit Fig. 2 is disconnected. A circuit is now established from battery and ground at repeating coil 305 over the talking conductors to testing device, Fig. 5. This circuit is obvious and need not be traced. 50 Again referring to the testing device, Fig. 5, it will be remembered that relays 510, 511 and 506 are held in an operated position. A test will now be made to ascertain whether relay 314 operated to disconnect ringing current from the line conductors. This test is made by again bridging relay 507 across the line conductors. If the ringing relay 314 did not operate when 55 the operating or tripping test was applied, the ringing current would remain connected to the line conductors and thus relay 507 would again be operated. Preparatory to making this test it is necessary to discharge 60 condenser 550 because this condenser will be charged from one side of the AC wave. If relay 314 has properly disconnected the ringing potential and rotated the incoming selector as described to position 16, battery 65 will be connected from repeating coil 305 to the line conductors. Therefore, should the condenser be charged in such direction that this battery and ground will cause it to discharge through the winding of relay 507, 70 said discharge would at times cause the operation of relay 507. Since relay 507 should only operate from ringing current if said ringing current has not been disconnected, the operation of relay 507 from condenser 75 discharge would be a false indication. Condenser 550 is discharged by bridging it across the tip and ring conductors. If the tip and ring conductors have not been disconnected from ringing potential it will not be discharged. However, if the ringing potential has been disconnected from the tip and ring conductors and battery and ground connected to said conductors, the discharge of 80 condenser 550 will take place. This circuit 85 may be traced from conductor 503 through condenser 550, left normal contact and armature of relay 508, right contact and armature of relay 511, left outer contact and armature of relay 510, upper contact of sequence switch spring 533 to conductor 502. Subsequent to the discharge of condenser 550, relay 507 is bridged across the line conductors by the operation of relay 508. The 90 circuit for actuating relay 508 may be traced from grounded battery through the contact of sequence switch spring 526, winding of relay 508, right outer normal contact and armature of relay 509, left outer normal contact and armature of relay 512, right contact and armature of relay 510, lower contact of sequence switch spring 524 to ground through left contact and armature of relay 506. The circuit is now established 95 for bridging relay across the line conductors. 100

This circuit may be traced from conductor 503 through condenser 550, winding of relay 507, lower contact of sequence switch spring 530, left contact and armature of relay 508, 5 right contact and armature of relay 511, left outer contact and armature of relay 510, upper contact of sequence switch spring 533 to conductor 502.

Should relay 507 be operated, such operation would indicate that ringing relay 314 had not operated to cut off the ringing potential when resistances 560 and 561 were bridged across the line conductors. To indicate this, the operation of relay 507 establishes a circuit for operating relay 513. This path may be traced from ground through the right upper contact of sequence switch spring 521, contact and armature of relay 507, right lower contact of sequence switch spring 527, right contact and armature of relay 508, winding of relay 513, lower contact of sequence switch spring 532, right winding of relay 506 to grounded battery. Relay 506 thereafter remains locked to the contact of relay 513 over the path which may be traced from grounded battery through the right winding of relay 506, lower contact of sequence switch spring 532, winding of relay 513, right armature and contact of relay 508, to ground through armature and contact of relay 513. This prevents the sequence switch 500 from moving beyond position 13 and thus the non-operation of ringing relay 314 will be indicated to the test man.

Assuming that the ringing relay 314 did properly operate when the described tripping test was connected to the line conductors, relays 507 and 513 are not operated and relay 506 remains under the control of interrupter 551. It will be remembered that relays 510 and 511 are operated and relay 506 is operated through interrupter 551. Upon the release of relay 506 a circuit is established for operating relay 512 as previously traced. The operation of relay 512 releases relay 510. A subsequent operation of relay 506 under the control of interrupter 551 establishes a circuit for operating relay 509 as previously traced and the subsequent release of relay 506 establishes an operating circuit for relay 510, as previously traced. Upon the subsequent operation of relay 503 under the control of interrupter 551 a circuit is established for actuating sequence switch magnet 500. This may be traced from grounded battery through the winding of magnet 500, lower contact of sequence switch spring 523, left outer contact and armature of relay 512, right contact and armature of relay 510, lower contact of sequence switch spring 524 to ground through left contact and armature of relay 503. The sequence switch 500 is thus rotated from position 12 to position

13, releasing relays 509, 510, 511 and 512. The subsequent release of relay 506 establishes a circuit for actuating sequence switch magnet 500. This may be traced from grounded battery through the winding of magnet 500, lower contact of sequence switch spring 525 to ground through left normal contact and armature of relay 506. The sequence switch is thus rotated from position 13 to 14. 75

Supervisory relay 312, in the incoming selector circuit, Fig. 3, is now tested by the testing device, Fig. 5. The supervisory relay 312 is first saturated by connecting a comparatively high current through its winding so that it will retain considerable residual magnetism during the time it is under test. This is done to simulate a short subscriber's line thereby preparing the supervisory relay 312 for test of its most difficult operation requirement. The circuit established for saturating supervisory relay 312 is in position 14 of sequence switch 500 and may be traced from grounded battery through the right lower winding of repeating coil 305, winding of relay 312 and resistance 313 in multiple, upper contact of sequence switch spring 331, brush 351, terminal 354, upper contacts of sequence switch spring 421, brush 438, terminal 441, conductor 503, resistance 560, upper contact of sequence switch spring 529, conductor 502, terminal 442, brush 439, lower contacts of sequence switch spring 422, terminal 355, brush 352, lower contact of sequence switch spring 332, right upper winding of repeating coil 305 to ground. This circuit remains established until relay 506 is again operated under the control of interrupter 551. The operation of relay 506 establishes a circuit for energizing sequence switch magnet 500 which may be traced from grounded battery through the winding of magnet 500, upper contact of sequence switch spring 524 to ground through contact and armature of relay 506. The sequence switch is thus rotated from position 14 to position 15 and upon a subsequent release of relay 506, an obvious circuit is established for energizing sequence switch magnet 500 to rotate the sequence switch from position 15 to position 16. 100 105 110 115 120

Upon the rotation of sequence switch 500 out of position 14, the circuit established for saturating supervisory relay 312 is opened. A circuit of high resistance, however, remains established through the winding of supervisory relay 312, through which it must release. This releasing circuit may be traced from grounded battery, through the right lower winding of repeating coil 305, winding of relay 312 and resistance 313 in multiple, left upper contact of sequence switch spring 331, brush 351, terminal 354, upper contacts of sequence switch spring 125 130 135 140 145 150 155 160 165 170 175 180 185 190 195 198 200 202 204 206 208 210 212 214 216 218 220 222 224 226 228 230 232 234 236 238 240 242 244 246 248 250 252 254 256 258 260 262 264 266 268 270 272 274 276 278 280 282 284 286 288 290 292 294 296 298 300 302 304 306 308 310 312 314 316 318 320 322 324 326 328 330 332 334 336 338 340 342 344 346 348 350 352 354 356 358 360 362 364 366 368 370 372 374 376 378 380 382 384 386 388 390 392 394 396 398 400 402 404 406 408 410 412 414 416 418 420 422 424 426 428 430 432 434 436 438 440 442 444 446 448 450 452 454 456 458 460 462 464 466 468 470 472 474 476 478 480 482 484 486 488 490 492 494 496 498 500 502 504 506 508 510 512 514 516 518 520 522 524 526 528 530 532 534 536 538 540 542 544 546 548 550 552 554 556 558 560 562 564 566 568 570 572 574 576 578 580 582 584 586 588 590 592 594 596 598 600 602 604 606 608 610 612 614 616 618 620 622 624 626 628 630 632 634 636 638 640 642 644 646 648 650 652 654 656 658 660 662 664 666 668 670 672 674 676 678 680 682 684 686 688 690 692 694 696 698 700 702 704 706 708 710 712 714 716 718 720 722 724 726 728 730 732 734 736 738 740 742 744 746 748 750 752 754 756 758 760 762 764 766 768 770 772 774 776 778 780 782 784 786 788 790 792 794 796 798 800 802 804 806 808 810 812 814 816 818 820 822 824 826 828 830 832 834 836 838 840 842 844 846 848 850 852 854 856 858 860 862 864 866 868 870 872 874 876 878 880 882 884 886 888 890 892 894 896 898 900 902 904 906 908 910 912 914 916 918 920 922 924 926 928 930 932 934 936 938 940 942 944 946 948 950 952 954 956 958 960 962 964 966 968 970 972 974 976 978 980 982 984 986 988 990 992 994 996 998 999 1000

421, brush 438, terminal 441, conductor 503, resistances 560, 561, 562, 563 and 564, winding of relay 513, lower and upper contacts of sequence switch spring 533, conductor 502, terminal 442, brush 439, lower contacts of sequence switch spring 422, terminal 355, brush 352, lower contact of sequence switch spring 332, right upper winding of repeating coil 305 to ground. Relay 513 is operated in this circuit.

Relay 506 is released during the rotation of the sequence switch from position 15 to position 16. A circuit is established in position 16 for again operating relay 506. This circuit may be traced from grounded battery, through the left winding of relay 506, to ground through the left upper contact of sequence switch spring 521. The operation of relay 506 establishes an obvious circuit for rotating sequence switch 500 from position 16 to 17.

A circuit is now established in position 17, of sequence switch 500 for intermittently operating and releasing the supervisory relay 312. The circuit for operating relay 312 may be traced from grounded battery, through the right lower winding of repeating coil 305, winding of relay 312 and resistance 313 in multiple and thence over the talking conductors of the incoming selector of Fig. 3 and the final selector of Fig. 4 to conductor 503 of testing device Fig. 5, thence through resistances 560, 561, and 562, right lower contact of sequence switch spring 534, interrupter 551, left hand lower contact of sequence switch spring 528, winding of relay 513, lower and upper contacts of sequence switch spring 533, and thence to ground at repeating coil 305 over the tip talking conductors previously traced. Each time interrupter 551 establishes a circuit through the conducting portion of its commutator, relay 312 is operated. A high resistance circuit is also established in position 17 through which the supervisory relay 312 must release to test its releasing adjustment. This high resistance circuit is the same as previously traced.

Assuming that the supervisory relay 312 is in correct adjustment and that it does operate and release properly, its operation establishes a circuit for operating relay 218 in the controlling device, Fig. 2. This circuit may be traced from ground through the contact and armature of relay 312, resistance 315, left upper winding of repeating coil 305, lower contact of sequence switch spring 324, tip of jack 304, tip of plug 234, tip conductor of patching cord 233, tip of plug 232, tip of jack 231, right outer contact and armature of relay 221, brush 206, terminal 19, of terminal arc 255, resistance 226, winding of relay 218, left inner normal contact and armature of relay 212, left inner contact and armature of relay

221, ring of jack 231, ring of plug 232, ring conductor of patching cord 233, ring of plug 234, ring of jack 304, upper contact of sequence switch spring 323, left lower winding of repeating coil 305, upper contacts of sequence switch spring 325, resistance 316, left upper contact of sequence switch spring 335 to grounded battery. Relay 218 operates in the circuit traced. It will be remembered that switch 200 has its brushes in contact with terminal 19 of the terminal arcs and thus relays 210 and 219 have remained operated. The operation of relay 210 establishes an obvious circuit for lighting lamp 227 which remains lighted until the operation of relay 218. As the supervisory relay 312 intermittently operates and releases relay 218 also intermittently operates and releases and thus lamp 227 is caused to flash. The flashing of lamp 227 indicates to the test man that the incoming selector switch Fig. 3, has properly functioned and that the adjustment of its relays is correct.

The test man, upon observation of the flashing lamp, operates disconnect key 241 establishing a circuit for operating relay 211. This circuit may be traced from ground through the contacts of key 241, left winding of relay 211 to grounded battery. Relay 211 in operating establishes a locking path for itself which may be traced from grounded battery through its right winding and right inner contact and armature to ground through the terminals of terminal arc 253 and brush 204. Relay 211 also establishes a circuit for actuating switch magnet 200 which may be traced from grounded battery through winding and contacts of magnet 200, right outer contact and armature of relay 211 to ground through the terminals of terminal arc 253 and brush 204. Switch 200 is thus rotated from terminal 19 to terminal 22 and with its brushes connected to terminal 22, a circuit is established for actuating switch magnet 200 from grounded battery through its winding and contacts to ground through brush 203 and terminal 22 of terminal arc 252. The switch is thus returned to its normal position.

Switch 200 in rotating from terminal 19 to its normal position opens all circuit paths to cause the release of all relays in the control circuit, Fig. 2.

It will be remembered that relay 311 is held in an operated position over the sleeve circuit extending to a ground in Fig. 2. Upon the restoration of switch 200 this circuit is opened causing the release of relay 311 which establishes an energizing circuit for sequence switch magnet 300. This may be traced from grounded battery through the winding of magnet 300, left upper contact of sequence switch spring 328, to ground

- through the left inner armature and contact of relay 311. This circuit remains established throughout sequence switch positions 16 and 17, thus rotating the sequence switch into position 18. In sequence switch position 18 a circuit is established for down-drive magnet 301. This circuit may be traced from grounded battery through the winding of magnet 301 to ground through the right upper and lower contacts of sequence switch spring 333. The incoming selector sequence switch elevator is thus returned to its normal resting position and brush 342 is brought into contact with commutator segment 346. A circuit is now established for actuating sequence switch magnet 300 to rotate the sequence switch to its normal position 1. This circuit may be traced from grounded battery through the winding of magnet 300, right upper contact of sequence switch spring 328, commutator segment 346, brush 342 to ground through the lower contact of sequence switch spring 333.
- Upon the downward movement of the incoming selector switch elevator its brushes are disengaged from the terminals connected to the final selector switch, Fig. 4, causing the release of relay 406. It will be remembered that relay 406 has been held in an operated position over the sleeve conductor extending to ground at sequence switch spring 330 of the incoming selector switch. The release of relay 406 establishes an energizing circuit for relay 407. This circuit may be traced from grounded battery through the left winding of relay 407, upper contacts of sequence switch spring 411 to ground through the right normal contact and armature of relay 406. The operation of relay 407 establishes an energizing circuit for sequence switch magnet 400 which may be traced from grounded battery through the winding of magnet 400, lower contact of sequence switch spring 413, left contact and armature of relay 407 to ground through the upper contact of sequence switch spring 410. The sequence switch is thus rotated from position 15 to position 16 and in rotating opens the operating circuit for relay 407 causing its release. The release of relay 407 establishes an energizing circuit for sequence switch magnet 400 which may be traced from grounded battery through the winding of magnet 400, right upper contact of sequence switch spring 413, left normal contact and armature of relay 407 to ground through the upper contact of sequence switch spring 410. The sequence switch is thus rotated from position 16 to position 17 and an obvious circuit is established in position 17 for rotating the sequence switch into position 18. The circuit is now established for down-drive magnet 401 which may be traced from grounded battery through the winding of magnet 401,

lower contact of sequence switch spring 426, right upper contact of sequence switch spring 417 to ground through the left upper contact of sequence switch spring 419. The final selector sequence switch elevator is thus returned to its normal position and brush 432 is brought into engagement with commutator segment 436. A circuit is thus established for energizing sequence switch magnet 400 to return to its normal position 1. This circuit may be traced from grounded battery through the winding of magnet 400, left upper contact of sequence switch spring 413 commutator segment 436, brush 432 to ground through the left upper contact of sequence switch spring 419.

The downward movement of the final selector switch elevator disengages brush 437 from terminal 440 removing the holding circuit for relay 505 causing its release. The release of relay 505 establishes an energizing circuit for sequence switch magnet 500 which may be traced from grounded battery through the winding of magnet 500, upper contact of sequence switch spring 523, right normal armature and contact of relay 505 to ground through the lower contact of sequence switch spring 521. This circuit remains established through sequence switch position 18 and the sequence switch is thus rotated to its normal position 1. It should be noted that upon the release of relay 505 grounded battery is connected through resistance 565, left normal contact and armature of relay 505, lower contact of sequence switch spring 520 to terminal 440. The testing device is thus maintained busy to other final selector switches until sequence switch 500 is returned to its normal position 1.

The apparatus of the testing device has now been restored to normal, the final selector switch and incoming selector switch have been returned to normal and the apparatus of Fig. 2 and Fig. 1 have been restored to normal. The testing system is now prepared to make other tests.

What is claimed is:

1. In a testing system, a testing device, an automatic switch to be tested, control circuits, means to position said switch by means of said control circuits, means to operate said testing device to test said control circuits, apparatus progressively operated during a service connection through auxiliary circuits associated with said switch, and auxiliary testing device and means to test said apparatus, said progressive operation and auxiliary circuits under the control of said auxiliary testing device.
2. In a testing system, a testing device, an automatic switch to be tested, control circuits, means to position said switch by means of said control circuits, means to operate said testing device to test said control circuits, relays and auxiliary circuits associated with said switch, and auxiliary testing device and means to test said apparatus, said progressive operation and auxiliary circuits under the control of said auxiliary testing device.

- ciated with said switch, another switch, an auxiliary testing device, means to direct said switches to seize said auxiliary testing device, and means to test said relays and 5 auxiliary circuits under the control of said auxiliary testing device.
3. In a testing system, a testing device, an automatic switch to be tested, control circuits, means to position said switch by 10 means of said control circuits, means to operate said testing device to test said control circuits, relays and auxiliary circuits associated with said switch, an auxiliary testing device, means to operate said testing device 15 to control selection of said auxiliary testing device, and means to test said relays and auxiliary circuits under the control of said auxiliary testing device.
4. In a testing system, a testing device, 20 an automatic switch to be tested, control circuits, means to position said switch by means of said control circuits, means to operate said testing device to test said control circuits, relays and auxiliary circuits associated with said switch, an automatically 25 progressive auxiliary testing device, and means to variably test said relays and auxiliary circuits under the control of said automatically progressive auxiliary testing device.
5. In a testing system, a testing device, 30 an automatic switch to be tested, control circuits, means to position said switch by means of said control circuits, means to operate said testing device to test said control circuits, apparatus progressively operated 35 during a service connection through auxiliary circuits associated with said switch, an auxiliary testing device, means to variably test said apparatus, said progressive operation 40 and auxiliary circuits under the control of said auxiliary testing device, and means to indicate the success of said tests.
6. In a testing system, a testing device, 45 an automatic switch to be tested, control circuits, means to position said switch by means of said control circuits, means to operate said testing device to test said control circuits, relays and auxiliary circuits associated with said switch, an automatically 50 progressive auxiliary testing device, means to variably test said relays and auxiliary circuits under the control of said automatically progressive auxiliary testing device, and means to indicate an unstandard 55 condition during said tests.
7. In a telephone exchange system, a primary testing device, a secondary testing device, an automatic selector switch, a source 60 of ringing potential, means in said automatic selector switch for automatically connecting said ringing potential to a selected line and for automatically disconnecting said ringing potential, means in said primary testing device for directing said automatic selector switch to said secondary test- 65 ing device, and means in said secondary testing device to automatically test the adjustments of said ringing potential connecting and disconnecting means.
8. In a testing system, an automatically 70 progressive testing device, a selector switch to be tested, relays and auxiliary circuits associated with said switch, a sending device, means to position said switch under the control of said sending device to establish connections to said testing device, and means to operate said testing device to test 75 said relays and auxiliary circuits.
9. In a testing system, an automatically progressive testing device, a selector switch 80 to be tested, ringing apparatus progressively associated with said switch, and means to operate said testing device to test said ringing apparatus.
10. In a testing system, a plurality of 85 testing devices, a common testing device and means to automatically select and put into service one of said testing devices and means to automatically associate therewith said common testing device.
11. In a testing system, a plurality of 90 testing devices, a common testing device, an automatic switch to be tested, means to associate one of said plurality of testing devices with said automatic switch, and means 95 to control said automatic switch to connect said common testing device with said associated testing device.
12. In a testing system, a plurality of 100 testing devices, an automatic switch to be tested, and means to automatically associate any idle one of said plurality of testing devices with said automatic switch.
13. In a testing system, a primary testing device, a plurality of secondary testing devices, an automatic switch to be tested, control circuits and auxiliary apparatus associated with said automatic switch, means 105 to operate said primary testing device to test said control circuits, and means to operate one of said secondary testing devices 110 to test said auxiliary apparatus.
14. In a telephone exchange system, a primary testing device, a plurality of secondary testing devices, an automatic switch, 115 a source of ringing potential, control circuits associated with said switch, apparatus associated with said automatic switch to automatically connect said ringing potential to a selected line and to automatically 120 disconnect said ringing potential, means to operate said primary testing device to test said control circuits and means to operate one of said secondary testing devices to make successive tests on the various adjustments 125 of said apparatus.
15. In a telephone exchange system, an automatic switch, sources of ringing potential, apparatus associated with said automatic switch to automatically connect said 130

- ringing potential to a selected line and to automatically disconnect said ringing potential, an automatically operated testing device, means to operate said testing device 5 to make successive tests on the various adjustments of said apparatus, and means to operate a signal to indicate the success of said tests.
16. In a telephone exchange system, an automatic switch, relays and auxiliary circuits associated with said switch, an automatic progressive testing device, means to operate said testing device to variably test said relays and auxiliary circuits, a signal, 10 means to operate said signal to indicate the success of said tests under the control of one of said relays.
17. In a telephone exchange system, a selector switch, a ringing circuit, apparatus associated with said selector switch to automatically connect said ringing circuit to a selected line and to automatically disconnect said ringing circuit, an automatically progressive testing device, means forming a part 20 of said ringing circuit to start the automatic progression of said testing device to make successive tests on the various adjustments of said apparatus.
18. In a telephone exchange system, a selector switch, a source of continuous ringing potential, apparatus associated with said automatic switch to automatically connect said ringing potential to a selected line, a progressive testing device, and means to 25 control the progress of said testing device by the application of said continuous ringing potential.
19. In a telephone exchange system, an automatic switch, control circuits, means to 30 position said switch by means of said control circuits, a progressively operable control switch associated with said automatic switch, a source of ringing potential, means to connect said ringing potential continuously 35 to a line in certain positions of said control switch, means to connect said ringing potential intermittently to a line in other of positions of said control switch, an automatically progressive testing device, means to 40 operate said testing device to test said applications of ringing potential, and means to indicate an unstandard condition during said test.
20. In a telephone exchange system, an automatic switch, a source of ringing potential, apparatus associated with said automatic switch to automatically connect said ringing potential intermittently to a selected line, an automatically progressive 45 testing device, and means to synchronize the progressive movement of said testing device with said intermittent application of ringing potential.
21. In a telephone exchange system, an automatic switch, a source of ringing current, a relay associated with said switch, means to conduct said ringing current through the winding of said relay to connect said ringing current to a selected line, means to adjust said relay to non-operate under one condition on said line when so connected and to operate under a subsequent condition on said line when so connected, an automatically progressive testing device, and means in said testing device to test said non-operate adjustment.
22. In a telephone exchange system, an automatic switch, a source of ringing current, a relay associated with said switch, means to conduct said ringing current through the winding of said relay to connect said ringing current to a selected line, means to adjust said relay to non-operate under one condition on said line when so connected and to operate under a subsequent condition on said line when so connected, an automatically progressive testing device, means in said testing device to test said non-operate adjustment, and means to make a plurality of said tests to increase the probability of testing at the desired point in the ringing current wave.
23. In a telephone exchange system, an automatic switch, a source of ringing current, a relay associated with said switch, means to conduct said ringing current through the winding of said relay to connect said ringing current to a selected line, means to test said relay to non-operate under one condition on said line when so connected and to operate under a subsequent condition on said line when so connected, an automatically progressive testing device, and means in said testing device to test said operate adjustment.
24. In a telephone exchange system, an automatic switch, a source of ringing current, a relay associated with said switch, means to conduct said ringing current through the winding of said relay to connect said ringing current to a selected line, means to adjust said relay to operate within a predetermined time period, an automatically progressive testing device, and means in said testing device to test said adjustment.
- In witness whereof, I hereunto subscribe my name this 27th day of June A. D., 1923.
- ARNOLD S. BERTELS.
